UNITED STATES PATENT OFFICE.

HERBERT FROOD, OF SOVEREIGN MILLS, CHAPEL-EN-LE-FRITH, ENGLAND.

LAMINATED SPRING.

Application filed June 2, 1924. Serial No. 717,420.

To all whom it may concern:

Be it known that I, HERBERT FROOD, a subject of the King of Great Britain and Ireland, and resident of Sovereign Mills, Chapel-en-le-Frith, in the county of Derby, England, have invented certain new and useful Improvements in and Relating to Laminated Springs, of which the following is a specification.

10 This invention relates to laminated or leaf springs for vehicles and other purposes.

It has been found that the interposition between the individual leaves of leaf springs of laminæ of material other than metal 15 which is resistant of the action of water, oil and heat and is further resistant to friction in the sense that its desirable properties are not detrimentally affected from the wear resisting point of view by friction due to slipping, presents numerous advantages.

The object of the present invention is to provide an improved construction of laminated or leaf spring whereby the individual leaves shall be effectively protected from 25 moisture and the non-metallic or friction material located between the leaves securely held in position.

According to this invention, the spring comprises metallic leaves which are individually encased in a covering of non-metallic material, which may if desired have a metallic reinforcement.

The casings for the individual leaves may be of tubular form or may be substantially 35 tubular, that is to say, formed by folding or bending a sheet of material so as to bring two opposite edges of the sheet substantially into contact. Alternatively, the casings may be formed by folding or bending in the 40 manner indicated and a joint made between the abutting edges. In a further alternative, the casings may be formed without a joint in any suitable manner, for instance, by moulding a suitable composition or by forming a tubular envelope by weaving or knitting.

The casings or envelopes may be affixed to the leaves of the springs by vulcanizing or otherwise.

50 The fibrous material employed in the construction of the leaves may be of vegetable, animal or mineral origin, or fibrous material from any two or more of these origins may be employed conjointly. As an example of suitable material, of which the casings

may be formed, we employ a combination of fibrous material such as asbestos, with an organic binder, preferably of an infusible character, for example, a combination of asbestos with infusible phenol formaldehyde 60 condensation products, may be mentioned.

Metal wires may if desired be embedded in or incorporated with the material of the casing for the purpose of reinforcing it.

The whole of the individual leaves of a 65 spring may be separately encased in accordance with the invention, but if desired the top or longest leaf may be left unencased or be encased for only a portion of its length, in order that connection between it and 70 other members, for instance, shackles and dumb-irons, may be facilitated.

In some cases it may be considered desirable to seal the ends of the casings of the leaves, thus completely enclosing the metal 75 and securing it from atmospheric and other destructive agencies and, if desired, lubricant may be introduced into the casings or between them. The casings may be formed with interior surfaces constituted by unbonded fibrous material, that is to say, the fibrous material or the fabric formed therefrom may be left in the soft or grey state, so as to act as a carrier or holder for a lubricant, as for instance, grease, oil or 80 graphite, or an anti-rust or other composition which it may be desired to have in direct contact with the metal leaves, the outside of the casing being of a water and wear-resisting character, or possessing other properties which are desirable in a spring inter-leaving.

Referring to the accompanying sheet of explanatory drawings:

Figure 1 is an elevation, Figure 2 a plan 95 and Figure 3 an elevation with part in section, of a laminated or leaf spring as made in accordance with this invention.

Figures 4 and 5 are sectional end views showing (to a larger scale) one leaf of such a 100 spring with modified forms or types of the covering or envelope therefor.

Each metallic leaf *a* of the spring is provided with a covering or envelope *b* of non-metallic material as hereinbefore described. 105 In the type shown by the end section at Figure 4 the covering or enveloping material *b* is folded upon the metal leaf *a* so as to bring the longitudinal edges of the cover into contact or adjacent each other. In the 110

form or type shown at Figure 5 the covering or enveloping material *b* is reinforced by metal wires as *c* embedded in or incorporated with the said material.

5 I claim:—

1. In laminated or leaf springs, a covering for each leaf formed of non-metallic material, and metallic reinforcing material within said covering.
- 10 2. In laminated or leaf springs, a covering for each leaf consisting of asbestos material impregnated with infusible phenol formaldehyde condensation product.

3. In laminated or leaf springs, a covering for each leaf of non-metallic material having the outer portion impregnated with infusible phenol formaldehyde condensation product and the inner portion unimpregnated to act as a carrier for the lubricant.

4. In laminated or leaf springs as claimed 20 in claim 2, wherein metallic reinforcing material is embedded within the covering.

In testimony whereof I have signed my name to this specification.

HERBERT FROOD.
